CLAIM

I claim the ornamental design for a data processing equipment, as shown and described.

DESCRIPTION

FIG. 1 is a rear elevation view of a data processing equipment; FIG. 2 is a front elevation view of a data processing equipment;

FIG. 3 is a bottom plan view of a data processing equipment;

FIG. 4 is a top plan view of a data processing equipment;

FIG. 5 is a right side elevation view of a data processing equipment;

FIG. 6 is a perspective view of a data processing equipment; and,

FIG. 7 is a second perspective view of a data processing equipment.

The left side of a data processing equipment forms no part of the claimed design except for what is shown in FIGS. 1 through 4.

Broken line areas show environmental structure and form no part of the claimed design.

1 Claim, 7 Drawing Sheets
